UNITED STATES PATENT OFFICE.

CHARLES H. LEINERT, OF CHICAGO, ILLINOIS.

COMPRESSOR.

1,123,327.

Specification of Letters Patent.

Patented Jan. 5, 1915.

Application filed May 21, 1913. Serial No. 769,035.

To all whom it may concern:

Be it known that I, CHARLES H. LEINERT, a citizen of the United States, residing at Chicago, in the county of Cook and State 5 of Illinois, have invented certain new and useful Improvements in Compressors, of which the following is a specification.

My invention relates to compressors, and refers particularly (although not exclusively) to compressors adapted for use in connection with cooling systems in which ammonia is employed, although my compressor may also be used for compressing air or other gases, and, in fact, may be employed as a vacuum machine. The principles involved in my compressor may also be employed for the particular type of air compressors known as blowing engines used in connection with blast furnaces.

20 The types of compressors which have heretofore been employed are known as single acting and double acting. In the case of a single-acting compressor, the gas is admitted to one side of a piston which 25 operates within a cylinder, and by reciprocation of the piston this gas is compressed. In the case of the double-acting compressors, gas is admitted to each side of the piston reciprocating within a cylinder, so that a compressing action takes place on movement of 30 the piston in either direction.

It is the object of my invention to increase and simplify the operation of compressors by the use of a quadruple-acting machine. 35 A pair of pistons is provided which are suitably connected with each other so that they reciprocate together. These pistons are located within a single cylinder, which at or near its center is provided with a partition 40 which is preferably movable and valved. In this way four compression spaces are provided within the cylinder, so that as the connected pistons reciprocate back and forth, the gas in two of the compression spaces is 45 simultaneously compressed while new gas is being admitted to the other two compression spaces, and upon movement of the pistons in the opposite direction the reverse action takes place. By operating the compressor in this manner, I have found that great simplicity of construction may be attained and a considerable saving of power

effected, both on account of the lessened weight and friction of the parts and on account of a cooling action which I will explain hereinafter.

In the quadruple-acting machine which I have just described, ammonia or other gas may be admitted to the four compression chambers at a plurality of pressures, and the gas in all of the compression spaces may then be compressed to a certain fixed pressure, or at a plurality of different pressures, if desired.

A further object of my invention is to prevent a rise of temperature of the gas which is admitted to and compressed in the compressor to the greatest possible extent, both for the purpose of economizing power in effecting the compression and in order to keep the various bearing parts of the machine cool to prevent undue wear. I accomplish this result by admitting gas to two of the compression spaces through the two piston rods, which are made hollow, valves being provided at the inner ends of these piston rods. The gas which passes through these piston rods is, of course, in an expanded and therefore cool condition, and serves to cool the piston rods, the bearings associated therewith and the walls of the piston itself.

A further object of my invention resides in so constructing the various parts that when the compressed gas is expelled from the compression spaces this expulsion is made complete so that there is no reexpansion of the gas into the compression spaces. This point is a very important one, since if any appreciable amount of compressed gas is allowed to remain in the compression spaces, on reexpansion of such gas, the entrance of further gas to the compression space is prevented.

A still further object of my invention relates to the provision of inlet and outlet valves for the compression spaces. These valves are so constructed, as will be explained in detail hereinafter, that they may readily be adjusted to open or close, as the case may be, at any desired pressure; this result being accomplished by regulating a suitable gas cushion.

A further object of my invention consists

in the use of interlocking packing rings on the piston, these rings being constructed so that expansion of the same is effected without the use of an underlying bull ring or springs.

6 A further object of my invention consists in the use of an oil separator, which is employed in connection with the compressed gas, the latter being forced through an extended path and brought into contact with 10 a plurality of corrugations which remove the oil and moisture from the compressed gas.

15 These and other advantages of my invention will be more readily understood by reference to the accompanying drawings, which show a preferred embodiment of my improvements, and in which,—

20 Figure 1 is a plan of my compressor, with the various connections used therefor; Fig. 2 is a side elevation of the parts shown in Fig. 1; Fig. 3 is an enlarged, vertical longitudinal section through the compression cylinder and the various parts associated therewith; and Fig. 4 is a vertical transverse section taken on the line 4—4 of Fig. 3.

25 The compressor is provided with pedestals 10 which are supported on the base 11. Also supported on the base 11 is the pillow block 12, which supports in suitable bearings the crank shaft 13. A yoke 14 is suitably connected to the crank-shaft 13 at one end, and at its opposite end is attached to a cross-head 15 which reciprocates within 35 a cross-head guide 16^a.

Attached to the ends of the cross-head 15 are the connecting rods 16, which are also attached to a cross-head 17 which reciprocates within a cross-head guide 18. The cross-heads 15 and 17 are rigidly attached to the 40 hollow piston-rods 19 and 20, so that on rotation of the main crank-shaft 13 the piston rods 19 and 20 are themselves reciprocated. The piston rod 19 at one end passes into the 45 main trunk stuffing-box 21, which at the same time acts as a suction chamber in connection with the branch inlet-pipe 22. Similarly, the hollow piston-rod 20 passes into the main trunk stuffing-box 23, which is connected with the branch inlet-pipe 24. Suitable packing rings are provided around the piston rods 19 and 20 to prevent leakage of gas as the piston rods are reciprocated within the main trunk stuffing-boxes 21 50 and 23.

55 The inner ends of the piston rods 19 and 20 project within the compressor cylinder represented as a whole by 25. The end of each piston rod is provided with a piston 60 26, a threaded connection being provided between the piston rod and the piston. Each of the pistons 26 is hollow and of semi-spherical shape, of the same contour as the two ends of the cylinder 25. Each of the 65 pistons 26 has an inner end member 27 pro-

vided with a flange 28. Between the periphery of the member 27 and the inner surface of the cylinder 25 are placed packing rings 29, 30 and 31. These rings are held in position by the flange 28, and the central ring 30, provided with offsets 32, serves to expand the rings 29 and 31 so that snug engagement is made with the inner surface of the cylinder, and the use of a bull ring or expanding springs is thereby avoided. 70 Fastened to the member 27 is a valve-seat member 33 provided with passages 34 and a sleeve 35. A valve 36 seats on the valve-seat member 33 and has an extension 37 within the sleeve 35. Fastened to this extension 37 by means of a screw-bolt 38 is a cap 39, which also engages the outer surface of the sleeve 35. Between the cap 39 and the valve-seat member 33 is a spring 40 which serves to normally keep the valve 36 seated 85 against the valve-seat member 33.

90 The compressor cylinder, represented as a whole by 25, consists of an outer casing 41 which is supported by the base 11 of the compressor, and within this casing are bushings 42, the water-cooling spaces 43 being formed between the bushings 42 and the casing 41. Between the casing 41 and the outer surfaces of the bushings 42 are provided recesses 41^a and 42^a, which preferably 95 have outlet passages 43^a connected therewith. After the bushings 42 have been inserted within the casing 41, hot metal, such as lead or similar composition, is poured through the passages 43^a and fills the annular recesses 100 formed by the recesses 41^a and 42^a, thereby serving to prevent leakage between the casing 41 and the bushings 42. The upper portion of the casing 41 is provided with an aperture 44 which is normally closed by a 105 valve-cap 45, and outside of this a water-jacket cap 46; the space between the valve-cap 45 and the water-jacket cap 46 being normally filled with cooling water.

110 Just inside of the valve-cap 45 is an annular space 47, which at its lower portion is provided with a pair of supporting lugs 48 recessed at 49^a. The lugs 48 serve to support valve-partitions 49 and 50. The valve-partition 49 is provided with a flange 51 which 115 is located just exterior to and fits over a flange 52 of the valve-partition 50. Between the partitions 49 and 50 are placed expansion springs 53, which serve to hold the partitions 49 and 50 against the ends of the 120 bushings 42, so that there is no communication between the annular space 47 and the inside of the cylinder 25. The partition 49 is provided with a valve-seat member 54, this seat-member being held in position by a 125 ring 55 having apertures 56 extending therethrough. A valve 57 engages the valve-seat member 54 and extends inwardly within the ring member 55. In a similar manner the partition 50 is provided with a valve-seat 130

member 54^a held in position by the ring member 55^a having passages 56^a. A valve 57^a extends through the ring member 55^a, and also has an extension 58 which extends within the inner hollow end of the valve 57. Between the valves 57 and 57^a is located an expansion spring 59, which serves to keep the valves 57 and 57^a in engagement with the respective valve-seat members 54 and 54^a.

10 The two ends of the cylinder 25 are provided with cylinder-heads 60 and 61. Each of these cylinder-heads is provided with suitable packing through which the piston rod 19 or 20, as the case may be, passes. Each 15 of the cylinder-heads 60 and 61 is provided with an inlet passage 62 which communicate with a valve chamber 63 closed on the outside by a cap 64. Integral with the cap 64 is a hollow extension 65, on the outside of which a valve 66, seating against a valve-seat 67, is located. The valve member 66 is provided with flanges 68 and 69. The valve-seat member 67 is held in position by a ring 70, which is connected with a ring 71, containing a rubber ring 72, by means of ribs 73. The housing 74 is fastened to the ring 71. A helical expansion spring 75 extends between the ring 72 and the flange 69. The cap 64 has fitted upon its end a cock 76 provided 30 with a passage 77 leading to the interior of extension 65 and may be brought in register with the passage 78 in the cap-member 64. The passage 78 communicates with the chamber 63. Each of the cylinder-heads 60 35 and 61 also contains a chamber 79, which is closed by means of a cap 80 having a hollow inward extension 81. At the base of the extension 81, the cap 80 is provided with an annular recess 82 at the bottom of which is a rubber ring 83. The valve 84 has a sleeve 85 inclosing the extension 81, and also has a piston-like end 86 which fits within the annular recess 82 in the cap 80. The spring 87 occupies a position between the valve 84 and the 40 base of the recess within the extension 81 of the cap 80. The valve 84 is normally seated by the spring 87 against a valve-seat member 88. A cock 89 extends through the cap 80 and has a passage 90 which is in communication 45 with the chamber 79, and on turning the cock is adapted to be brought into register with a passage 91 which communicates with the annular recess 82. Each of the cylinder-heads 60 and 61 may be provided with one or 50 more of the inlet valves 66 and outlet valves 84 of the type which I have just described.

The annular space 47 communicates with the oil separator, which is indicated as a whole by 92. This oil separator, as most 60 clearly indicated in Fig. 4, is provided with a central passage 93 which communicates at its lower end with the space between said passage and the outer casing 94 of the oil separator. This space is provided with a spirally-disposed partition 95, the lower sur-

face of which is provided with corrugations 96, thereby forming a spiral passage 97 through which the gas travels in a manner which will presently be explained. The upper end of the passage 97 is closed by a ball-check valve 98; this ball-check valve serving to normally close communication between the passage 97 and the pipe 99 which leads to the ammonia condenser or other similar apparatus to which the compressed gas is to 75 be delivered. Pipes 100 lead from the chambers 79 associated with the outlet valves 84 to the passage 93 in the oil separator 92. The lower end of the oil separator 92 is provided with a discharge pipe 101 for carrying 80 off oil or condensed liquid.

Associated with my compressor a bypass header 102 may be employed, to which may lead supply-pipes 103, 104, 105 and 106. Between each of these pipes a valve 85 107 is provided in the header 102, so that the latter is divided into a plurality of sections. Each of the pipes 103, 104, 105 and 106 is also provided with a valve 108. The pipe 22 leads from the header 102 to the 90 main truck stuffing-box 21, and the pipe 24 leads from the header to the main trunk stuffing-box 23. A pipe 109 leads from the header 102 to the inlet passage 62 in the cylinder-head 60, and a pipe 110 leads from 95 the header 102 to the inlet passage 62 in the cylinder-head 61.

Having thus described the various parts which are used in my improved compressor, the operation of the same will now be 100 readily understood. Ammonia or other gas to be compressed is supplied to the various inlets of the compressor through the pipes 22, 109, 110 and 24. It will be evident that by proper adjustment of the 105 valves 107 in the header 102, and the valves 108 in the pipes 103, 104, 105 and 106, the entrance pipes 22, 109, 110 and 24 may be supplied with gas at a plurality of different pressures. As the main crank-shaft 13 is 110 rotated, the two pistons 26 are reciprocated (by means of the connections explained above) within the bushings 42 of the cylinder 25. Let us assume that the pistons are being moved to the right from the positions 115 indicated in Figs. 1, 2 and 3. As this travel takes place, a vacuum is formed in the space to the left of the left-hand piston 26. This results in opening the valve 66 against the tension of the spring 75, and 120 gas is allowed to pass from the passage 62 in the cylinder-head 60 into that portion of the cylinder located to the left of the piston attached to the piston-rod 19. At the same time, the gas which is located between the left-hand piston and the partition 49 is compressed, and the valve 57 is thereby unseated, allowing this gas to pass through the openings 56 into the annular space 47 to the passage 93 in the oil sepa- 130

rator. This action continues until the left-hand piston 26 has reached a point in its travel where it approaches the partition 49. When this happens, the partition 49 as a whole is then moved against the tension of the springs 53 and unseated from the end of the bushing 42, so that the gas passes directly from the interior of the cylinder to the annular space 47. The piston may then engage the partition 49, so that absolutely all of the gas within this portion of the cylinder is expelled into the annular space 47. It will be evident that while this action is taking place, the partition 50 is being forced more firmly against the ends of the right-hand bushing 42. In the meantime the right-hand piston 26 is traveling toward the cylinder-head 61. The gas in that portion of the cylinder between the right-hand piston 26 and the cylinder-head 61 is compressed, and when it reaches the predetermined pressure the outlet valve 84 is unseated and the compressed gas passes through the pipe 100 to the passage 93 in the oil separator 92. At the same time, the valve 36 in the right-hand piston 26 is unseated and the gas contained within the hollow piston-rod 20 is allowed to pass into the space between the right-hand piston 26 and the partition 50. Inasmuch as this gas has been previously expanded, it serves to keep the piston rod and the piston at a low temperature, preventing heating of the bearings. It will also be clear that inasmuch as the piston 26 is hollow, it acts as a trap for catching scale or mechanical impurities of other description which may be contained within the gas. When the piston rods 19 and 20 are moved in the opposite direction, it will be apparent that exactly the reverse operation to that which has just been described takes place; that is, gas will be admitted to the portion of the cylinder between the left-hand piston 26 and the partition 49 and to the portion of the cylinder between the right-hand piston 26 and the cylinder-head 61, while the gas will be expelled through the outlet valve 84 of the cylinder-head 60 and through the partition 50. It will thus be apparent that there are four compression spaces within the cylinder 25, gas being compressed in two of these spaces at any one time, and being admitted to the other two by suction at the same time.

I have employed the cock 76 in connection with the valve 66 in order to easily regulate the pressure at which the valve operates. If the cock is turned so that communication between the passages 77 and 78 is interrupted, it will be evident that the valve 66 will unseat with great difficulty, since such unseating would tend to cause a vacuum within the hollow extension 65 of the

cap 64. On the other hand, if the passage 65 77 is brought fully into register with the passage 78, the valve 66 unseats very easily, since gas is constantly supplied through the passages 78 and 77 to the interior of the extension 65. By suitable regulation of the 70 cock 76, therefore, the valve 66 may be unseated at any desired degree of suction. The cock 89 used in connection with the outlet valve 84 operates on a similar principle. If communication between the passages 90 and 75 91 is entirely interrupted, the valve 84 will open with difficulty, since outward movement of this valve must be against an air cushion within the annular recess 82. If, on the other hand, it is desired to have the 80 valve open very easily, the passage 90 is brought into register with the passage 91. The area of the piston-like flange 86 is somewhat larger than that of the valve 84, and since the pressure of gas within the 85 chamber 79 is at the maximum to which it is desired to compress the gas, the valve 84 may open at a comparatively low pressure within the cylinder on account of the higher pressure within the chamber 79, the greater 90 area of the piston-like flange 86, and the fact that the gas within the annular recess 82 is readily expelled through the passages 91 and 90. This action is particularly desirable in ordinary operation, since it causes 95 the gas to be expelled from the cylinder immediately when the piston starts to move toward the outlet valve. The rubber rings 83 and 72 are provided in connection with the outlet and inlet valves in order to provide 100 cushioning means for the same.

As previously explained, the compressed gas passes to the passage 93 of the oil separator, and thence downwardly through this passage to the bottom of the casing 94. The 105 gas next passes through the spiral passage 97 and comes in contact with the corrugations 96, which serve to remove oil and liquid. These drop from the corrugations onto the smooth surface at the top of the 110 spiral partition 95 and are carried down to the bottom of the oil separator by gravity, and then pass out through the discharge pipe 101. From the passage 97 the gas passes the ball-check valve 98 and goes to 115 the pipe 99, the ball-check valve 98 serving to prevent any return of compressed gas which has once passed this valve.

It will be apparent to those skilled in the art that many changes could be made in the 120 detail construction of the various parts which I have described without departing from the spirit or scope of my invention, or sacrificing any of the advantages thereof.

What I claim is:

1. In a compressor, the combination of a cylinder, two pistons therein and an intermediate partition, and means for exhaust-

ing compressed fluid both through and around said partition, substantially as described.

2. In a compressor, the combination of a cylinder, two pistons, an intermediate partition in said cylinder, means for exhausting compressed fluid both through and around said partition, and means for supplying fluid to be compressed, said means including a valved passage through each of said pistons, substantially as described.

3. In a compressor, the combination of a cylinder, two pistons reciprocably mounted within said cylinder, said pistons being provided with hollow stems, a partition in said cylinder, said partition being located between said pistons, means for exhausting compressed fluid through and around said partition, and means for admitting fluid to be compressed through said hollow stem, substantially as described.

4. In a quadruple acting compressor, the combination of a cylinder, two pistons mounted therein, an intermediate two-part, expandible partition located between said pistons, and means for admitting fluid through said pistons, compressed fluid escaping around the peripheries of said partitions, substantially as described.

30 5. In a compressor, the combination of a cylinder having a pair of bodily movable transverse partitions in its central portion, an outlet passage communicating with the space between said partitions and on bodily movement of one of said partitions communicating with said cylinder, a pair of pistons within said cylinder, said pistons being located on opposite sides of said partitions, and means for reciprocating said

40 pistons in unison, substantially as described.

6. In a compressor, the combination of a cylinder having a pair of bodily movable valved transverse partitions in its central portion, an outlet passage communicating with the space between said partitions and on bodily movement of one of said partitions communicating with said cylinder, a pair of pistons within said cylinder, said pistons being located on opposite sides of said partitions, means for reciprocating the said pistons in unison, and means for admitting gas to said cylinder between each of

said pistons and said partitions, substantially as described.

7. In a compressor, the combination of a cylinder having a pair of bodily movable valved transverse partitions in its central portion, an outlet passage communicating with the space between said partitions and on bodily movement of one of said partitions communicating with said cylinder, a pair of pistons within said cylinder, said pistons being located on opposite sides of said partitions, means for reciprocating said pistons in unison, means for admitting gas to said cylinder between each of said pistons and said partitions, inlet means for admitting gas to said cylinder between each of said pistons and the adjacent end of said cylinder, and outlet means from said cylinder between each of said pistons and the adjacent end of the cylinder, substantially as described.

8. A moisture separator for gases, comprising a casing, a passage through said casing, and corrugations on the roof of said passage for separating the moisture from said gases, substantially as described.

9. A moisture separator for gases, comprising a casing, a passage through said casing, corrugations on the roof of said passage for separating the moisture from said gases, and a discharge outlet leading from said casing, whereby the separated moisture is carried away from said casing, substantially as described.

10. In a compressor, the combination of a cylinder having a pair of bodily movable valved transverse partitions in its central portion, resilient means for normally keeping said partitions separated from each other, an outlet passage communicating with the space between said partitions and on bodily movement of one of said partitions communicating with said cylinder, a pair of pistons within said cylinder, said pistons being located at opposite sides of said partitions, and means for reciprocating said pistons in unison, substantially as described.

CHARLES H. LEINERT.
